United States Patent Office

Des. 232,668
Patented Sept. 10, 1974

232,668

HAT

John C. De Monbrun, 309 N. Reese Place,
Burbank, Calif. 91506

Filed Mar. 7, 1973, Ser. No. 338,738

Term of patent 14 years

Int. Cl. D2—03

U.S. Cl. D2—257

Fig. 1

Fig. 2

Fig. 3

FIG. 1 is a front perspective view of a hat showing my new design;

FIG. 2 is a plan view in flat position; and

FIG. 3 is an edge view in flat position.

The dotted lines indicate scoring for bending.

I claim:

The design for a hat, substantially as shown and described.
